HOLDER FOR A PAIR OF SPECTACLES AND A PENCIL OR THE LIKE

Albert T. Cherry, 1103 S. Pasadena, Pasadena, Fla.

Filed Apr. 3, 1961, Ser. No. 64,573

Term of patent 14 years

(Cl. D57—1)

Fig. 1

Fig. 2

Fig. 3

Fig. 4

FIG. 1 is a front elevational view of a holder for a pair of spectacles and a pencil or the like showing my new design.

FIG. 2 is a rear elevational view thereof;

FIG. 3 is an end view thereof; and

FIG. 4 is a sectional view taken along line 4—4 of FIG. 1.

I claim:

The ornamental design for a holder for a pair of spectacles and pencil or the like, as shown.
